UNITED STATES PATENT OFFICE.

JACOB OTTO LUNDBERG, OF FLATEBY, NEAR LILLESTRÖMMEN, NORWAY.

PROCESS OF PRODUCING CHEMICAL WOOD-PULP.

1,257,290.

Specification of Letters Patent. Patented Feb. 19, 1918.

Application filed November 9, 1914. Serial No. 871,185.

To all whom it may concern:

Be it known that I, JACOB OTTO LUNDBERG, a subject of the King of Sweden, residing at Flateby, near Lilleströmmen, Norway, 5 have invented certain new and useful Improvements in Processes of Producing Chemical Wood-Pulp; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of this 15 specification.

The present invention relates to the manufacture of chemical wood pulp according to the sulfate or soda method and consists in an improvement in the method of supplying the heat necessary for the digesting operation. As is known the usual method of supplying the heat is to introduce steam into the digester, when this latter has been charged with wood and digesting liquor. 25 By this method however great quantities of water will be introduced into the digester so that the digesting liquor is highly diluted during the digesting operation. For various reasons this is a very great disadvantage and it has therefore been proposed to effect the raising of the temperature by maintaining the digesting liquid alone or together with the wood or other material to be treated in circulation through a special heating apparatus outside of the boiler. 30 This method is however also connected with various disadvantages. Thus the raising of the temperature takes a considerable time while on the other hand the circulation is 35 rendered difficult by the wood or other fibrous material under treatment.

According to the present invention the heating is effected in the manner that the quantity of liquor which at the beginning 45 of each digesting operation is introduced into the digesting boiler containing the wood or other fibrous material to be treated is preheated under pressure to such a high temperature that the principal amount of 50 heat necessary for the digesting operation is supplied by means of this quantity of preheated liquid.

The heating of the digesting liquor may be effected in reservoirs of any suitable form 55 and arrangement (for instance in vessels of a spherical, cylindrical or tubular shape or

in a system of vessels or pipes and the like) from which the hot liquor is blown into the digester in the quantity necessary for each digesting operation. A small quantity of 60 heat may in some instances also be supplied to the digester in a known manner. The process may for instance be carried out in the manner below described reference being had to the accompanying diagrammatic 65 drawing which illustrates a plant for carrying out the process.

In the drawing 1 designates a reservoir for fresh digesting liquor. 2 is a reservoir for "black liquor" (that is liquor which 70 has already been used), 3 and 4 designate the digesters.

5—10 designate connection pipes between the reservoirs and the digesters.

11 and 12 are steam pipes for effecting 75 the heating of the liquor in the reservoirs. Instead of arranging steam pipes inside of the reservoirs other indirect heating methods may of course be employed. The fresh liquor is heated in the reservoir 1 to 80 a comparatively high temperature for instance 180° C. Higher or lower temperatures for instance down to 140° C. may however also be employed without departing from the idea of this invention. In the following description it is assumed that the 85 digester 3 contains a charge, which has just been finished while the digester 4 is empty. The valves in the pipes 10 and 7 are now opened and the black liquor from the digester 3 in which a pressure of about 8 kg. per cm² may be assumed to prevail, is blown into the black lye reservoir 2 whereupon the digester is emptied in the usual manner. It may now be assumed that the black 90 liquor in the reservoir 2 is brought under a pressure of about 5 kg. per cm².

The charging of the digester 4 is now effected by first filling the digester with wood, whereupon a part of the black liquor 100 in the reservoir 2 is blown into the digester.

The digester is then filled with highly heated fresh liquor which is blown into the digester from the reservoir 1. The digesting operation then continues while supplying some heat in the usual manner. The emptying and charging of the digester is then continued in the manner above described.

The process is preferably carried out in 110 such manner that the temperature falls from the beginning of the digesting operation

until it is finished, but it may also in some cases be of advantage to maintain the temperature constant during the whole digesting operation or to cause a small rise in 5 temperature at a certain stage of the operation.

Before the reservoir 2 is charged with 10 fresh liquor to be heated it is of advantage to empty the same completely and to do away with the pressure in the same by blowing off steam. Hereby the use of high pressure pumps for filling the reservoirs is avoided.

By working according to the present invention which may of course be modified in 15 various manners, very important advantages are obtained over the usual methods. Thus it has been found, that the formation 20 of malodorous substances (mercaptanes and the like) which takes place in connection with the usual method of boiling, is quite insignificant when the process is carried out in accordance with the present invention. Moreover the plant and apparatus necessary 25 for carrying the invention into effect is very simple for instance as regards pipe conduits, valves and the like. The consumption of steam is uniform and continuous, which as will be understood is of the greatest advantage. Further the black liquor obtained is 30 of a much better quality, than that obtained according to the usual methods, so that the recovering of soda from the same becomes more rational. Another advantage consists 35 therein that a white liquor (freshly prepared liquor) of a lower concentration can be employed because the liquor is not diluted during the digesting operation as is the case when the quantity of heat necessary is supplied by means of steam directly introduced 40 into the digester.

As is well known it is usual in the soda cellulose factories to preheat the liquor to 45 some extent before it is supplied to the digesters but the heat which has been supplied in this manner has been much too small to reduce to any considerable degree the quantity of heat to be supplied to the digester during the digesting operation.

50 I claim:

1. The process of digesting wood pulp by the sulphate or soda process, which comprises filling a digester with the wood to be treated, storing the digesting liquor in a 55 separate container, indirectly steam-heating the liquor therein under pressure without circulation of the same by passing steam under high pressure in a conduit through

the container out of contact with the liquid so as to produce a temperature sufficiently 60 high that the amount of heat necessary for the digesting process is stored in the liquor, supplying the liquor so heated to the digester in a quantity sufficient to simultaneously effect the digesting and supply the 65 necessary heat, and completing the digestion without circulating the liquor through the digester.

2. The process of digesting wood pulp by the sulfate or soda process which comprises, 70 filling a digester with the wood to be treated, storing the digesting liquor in a separate container, heating a quantity of black liquor in a separate container, supplying the heated liquor under pressure to the digester, 75 heating freshly prepared digesting solution in a separate container to a high temperature without circulation of the same by passing steam under high pressure through the solution out of contact therewith so as 80 to produce so high a temperature that the heat necessary for essentially the whole digesting process is stored in the solution, supplying a quantity of the solution so heated to the digester, and completing the digestion 85 without circulating the liquid contents of the digester.

3. The process of digesting wood pulp by the sulfate or soda process which comprises filling a digester with wood to be treated, 90 drawing off the black liquor from a digester into a separate container, reheating the liquor in the latter by passing steam under pressure through said liquor out of contact therewith, supplying a portion of the heated 95 liquor to the digester containing the wood, heating a freshly prepared digesting solution in a separate container without circulation of the same by passing steam under high pressure through the solution out of 100 contact therewith so as to produce a temperature sufficiently high that the heat necessary for essentially the whole digesting process is stored in the solution, supplying a quantity of the solution so heated to the 105 charged digester, and completing the digestion without circulating the liquid contents of the digester.

In testimony that I claim the foregoing as my invention, I have signed my name in 110 presence of two subscribing witnesses.

JACOB OTTO LUNDBERG.
